COMBINED CIGARETTE REST AND ASH TRAY

Filed July 7, 1931

INVENTOR
Jacob E. Neahr.
BY John Waldheim
ATTORNEY

UNITED STATES PATENT OFFICE

JACOB E. NEAHR, OF SCARSDALE, NEW YORK

DESIGN FOR A COMBINED CIGARETTE REST AND ASH TRAY

Application filed July 7, 1931. Serial No. 40,440. Term of patent 3½ years.

To all whom it may concern:

Be it known that I, JACOB E. NEAHR, a citizen of the United States, residing at 18 Greenacres Avenue, Scarsdale, New York, have invented a new, original, and ornamental Design for a Combined Cigarette Rest and Ash Tray, of which the following is a specification, reference being had to the accompanying drawing, forming a part thereof.

The figure is a perspective view of the combined cigarette rest and ash tray showing my new design.

I claim:

The ornamental design for a combined cigarette rest and ash tray as shown.

JACOB E. NEAHR.
